PHONOGRAPHIC APPARATUS

Edward W. Kellogg, Moorestown, N. J., assignor
to Radio Corporation of America, a corpora-
tion of Delaware

Application July 29, 1939, Serial No. 287,293

4 Claims. (CL. 274—13)

This invention relates to phonographic apparatus of the type employing a cutter head which is moved radially across a blank disc to cut a groove therein, and more particularly to the driving and guiding mechanisms for the cutter head.

In recording machines of this type, the cutter is usually mounted on a carriage arranged for sliding movement on a pair of guide rails. Such carriages are made quite heavy, and the friction between them and the guide rails is usually sufficiently great to make the lead screw by means of which the carriage and cutter are driven across the turntable require enough power to react appreciably on the turntable driving system, thereby impairing the speed constancy of the rotating turntable and record blank. To reduce the aforementioned friction, it is possible, of course, to employ ball bearing rollers. However, space does not always permit use of such rollers, and even this expedient does not completely eliminate irregularities in friction, owing to particles of dirt or slight rough spots on the rails, as well as bearing imperfections. Such irregularities affect the uniformity of motion of the cutter carriage, and the least imperfections in this respect become apparent on the surface of the record.

In accordance with my invention for the purpose of minimizing friction on the rails, I make use of the principle that when there is continuous motion between the surfaces which are frictionally engaged, a change in direction or velocity of the relative motion has comparatively little effect on the frictional force developed between the two surfaces. In other words, the incremental friction is almost zero. It is particularly advantageous if the continuous motion is at right angles to the motion for which the minimizing of friction is desired. There is, with this superimposed motion, no possibility of sticking or catching, and, moreover, lubrication is improved by a better film of oil or grease.

The primary object of my present invention is to provide an improved disc recording machine which will be free from the aforementioned objections.

More particularly, it is an object of my invention to provide, in machines of the type set forth, a mechanism for feeding and guiding the cutter across the record with the friction load on the lead screw greatly reduced.

Another object of my present invention is to provide improved phonographic apparatus as

aforsaid in which more uniform cutter feed is obtained.

Still another object of my present invention is to provide an improved disc recording machine in which the reaction of the load of the cutter carriage on the turntable driving system will be greatly reduced.

It is also an object of my present invention to provide, in a machine of the type set forth, an improved carriage mounting which is simple in construction and highly efficient in operation.

According to the present invention, I provide guide rails in the form of round bars (that is, bars which are circular in cross-section) and cause these to rotate in journal bearings, the rails supporting the cutter head carriage for sliding movement thereon. Thus, the relative motion between the guide rails and the cutter carriage is principally at right angles to the direction of travel of the carriage in sliding along the rails. The rotation of the rails can be slow, and since a variation in their speed has no effect on the travel of the cutter carriage, the rails can be driven independently of the turntable, employing a source of power which will not be harmed by any irregularities in this small load.

The novel features that I consider characteristic of my invention are set forth with particularity in the appended claims. The invention itself, however, both as to its organization and method of operation, together with additional objects and advantages thereof, will best be understood from the following description of one embodiment thereof, when read in connection with the accompanying drawing, in which

Figure 1 is a top plan view of a disc recording machine employing one form of my invention, and

Figure 2 is a side elevation thereof.

Referring more particularly to the drawing, wherein similar reference numerals designate corresponding parts throughout, there is shown a frame comprising bed plate 1 provided with a pair of spaced standards 3. The plate 1 supports a motor 5 which, through a belt 7, drives a pulley 9 on a turntable shaft 11, the shaft 11 carrying a record supporting turntable 13 at its upper end.

Fixed to the shaft 11 is a worm 15 in mesh with a gear 17 which, through gearing 19, drives a lead screw 21 adapted to drive a sound translating device, such as a cutter 23, across a blank record disc R on the turntable 13. The cutter is carried on a head 25 which is fixed to a carriage 27 slidably carried on a pair of parallel

guide rails 28 and 29 rotatably carried in the standards 3 and extending through journal bearings 27a in the carriage 27. The weight of the carriage 27 is transmitted to the rails 28 and 29 through bearings 27a. The rails, in turn, are supported in stationary bearings 30 in the standards 3. The guide rails 28 and 29 are disposed adjacent the turntable and are circular in cross-section, as are also the bearings 27a. Motion is imparted to the carriage 27 and the parts carried thereby through a half nut or the like 26 in engagement with the lead screw 21 in conventional manner, any suitable mechanism 42, of which many are well known in the art, being employed 10 to disengage the half nut 26 from the lead screw 21 when desired.

One of the standards 3 supports a motor 31, the shaft of which is provided with a worm 33 in mesh with a gear 35 on a shaft 31. On the opposite end of the shaft 31 is a gear 39 which meshes with the gear 41 of a train of gears 41, 43, 45, the gear 41 being fixed to the guide rail 28 and the gear 45 being fixed to the guide rail 29. The gears of this train are connected to the lead screw 21.

When the motor 5 is energized, power is delivered therefrom to the carriage 27 through the belt 7, the pulley 9, the shaft 11, its worm 15, the gears 17 and 19, and finally the lead screw 21 and the half nut 26 to effect movement of the carriage mechanism longitudinally of the guide rails 28 and 29 and thus movement of the cutter 23 radially across the record blank R. At the same time, the motor 31 may be energized to effect rotation of the guide rails 28 and 29 in the journal bearings 27a, the rotation of the guide rails 28 and 29 taking place in a direction at right angles to the movement of the carriage 27. This greatly reduces the friction load on the lead screw 21, thereby reducing the reaction of such load of the turntable driving system, and thereby insuring more uniform feeding of the cutter 23 across the record blank R.

Although I have shown and described but one embodiment of my invention, it will be apparent to those skilled in the art that many other variations thereof are possible. I, therefore, do not wish to limit myself except insofar as is made necessary by the prior art and by the spirit of 50 the appended claims.

I claim as my invention:

1. In phonographic apparatus, the combination of a turntable, guide means rotatably disposed adjacent said turntable, a sound translating device slidably carried by said guide means for longitudinal movement thereon relative to said turntable, means including a motor for sliding said device along said guide means, and a second motor coupled to said guide means for rotating said guide means during sliding movement 10 of said device thereon.

2. In phonographic apparatus, the combination of a frame, a pair of guide rails rotatably carried on said frame, means including a motor for rotating said guide rails, a carriage slidably 15 mounted on said guide rails for longitudinal movement thereon, a sound translating device on said carriage, and means including a second motor for sliding said carriage along said rails while said rails are rotating.

3. The invention set forth in claim 2 characterized in that said guide rails are circular in cross-section, and characterized further in that said carriage is provided with a plurality of journal bearings through which said guide rails extend.

4. In a phonographic apparatus, the combination of a frame, a turntable rotatably supported on said frame, a pair of guide rails of circular cross section rotatably carried on said frame, said 30 guide rails being parallel to each other and to said turntable, a motor carried by said frame and coupled to said guide rails for rotating said rails, a carriage having a plurality of journal bearings 35 thereon, said guide rails extending through said bearings and said carriage being slideable longitudinally on said guide rails, a sound translating device on said carriage, a second motor carried by said frame, carriage feeding means for positively feeding said sound translating device across a 40 record on said turntable, means for selectively coupling said carriage to and uncoupling said carriage from said feeding means at will, and power transmitting means interposed between 45 said second named motor and said carriage feeding means for driving said carriage feeding means separately from said guide rails.

EDWARD W. KELLOGG. 50
